Specification for Design.

Patented Feb. 27, 1917.

Application filed September 12, 1916. Serial No. 119,775. Term of patent 14 years.

To all whom it may concern:

Be it known that I, WILLIAM D. FREESE, a citizen of the United States, residing at Akron, in the county of Summit and State of Ohio, have invented a new, original, and ornamental Design for Tire-Treads, of which the following is a specification, reference being had to the accompanying drawing, forming a part thereof.

Figure 1 is a plan view of the tire tread showing my new design; and

Copies of this patent may be obtained for five cents each, by addressing the "Commissioner of Patents, Washington, D. C."

Fig. 2 is a transverse sectional view.

I claim:

The ornamental design for a tire tread, as shown.

WILLIAM D. FREESE.
